UNITED STATES PATENT OFFICE.

MILLARD GILMORE, OF CHICAGO, ILLINOIS, ASSIGNOR TO VARIETY MANUFACTURING COMPANY, OF CHICAGO, ILLINOIS, A CORPORATION OF ILLINOIS.

FIRE-DOOR.

1,147,857.

Specification of Letters Patent. Patented July 27, 1915.

Application filed June 15, 1914. Serial No. 845,049.

To all whom it may concern:

Be it known that I, MILLARD GILMORE, a citizen of the United States, and a resident of Chicago, in the county of Cook and State 5 of Illinois, have invented a certain new and useful Improvement in Fire-Doors, of which the following is a full, clear, concise, and exact description, reference being had to the accompanying drawings, forming a part 10 of this specification.

This invention relates to fire doors and is more especially concerned with means for causing a correct operation of automatic fire doors.

15 In apparatus of this class, a non-combustible shutter or curtain is caused to close in front of an opening in the building, such as a door, window, or the like, when a predetermined temperature indicative of a 20 danger condition has been reached. The requirements for a successful device of this kind are extremely severe. The apparatus must be in a condition of readiness at all 25 times and must respond correctly to the condition for which it has been set. Failure to operate might be attended with the gravest consequences and it is obvious that only a structure of absolute reliability may be safely employed. This class of apparatus is not 30 used except under emergency conditions and is rarely inspected, so, unless the apparatus is inherently reliable, it is of no value as a protection against fire and fosters a false sense of security and is thereby worse than 35 useless.

One of the objects of the present invention is to provide an automatic fire door of improved construction which will embody to a maximum degree the qualities of reliability 40 in action, simplicity and ruggedness.

Another object is to provide an automatic fire door which may be easily and readily set and which will be positive in operation.

In the accompanying drawings, Figure 1 45 is a front elevation, with parts broken away, of a fire door embodying my invention, showing the structure as applied to a doorway; Fig. 2 is a cross-section of the same on the line 2-2 of Fig. 1; Fig. 3 is a side elevation of the fire door as viewed from the left

of Fig. 1; and Fig. 4 is a fragmentary view slightly enlarged of a section on the line 4-4 of Fig. 1.

The shutter proper is composed of a number of interlocked sections which are preferably made of metal strips having bearings so as to produce a flexible structure. This shutter or curtain 5 is best shown in Fig. 4. The curtain is normally rolled up on a roller 6 by the action of a spring 7, one end of 60 which spring is attached to a collar 8 and the other end of which is attached to the collar 10 which forms one end of the drum. The collar 8 is secured to the shaft 11 so as to produce the effect of the well known shade- 65 roller. The shaft 11 is provided with bearings 12 and 13 in the ends of the casing 15. The initial tension of spring 7 may be adjusted by means of the disk 16 which is fastened to the extension of shaft 11. The disk 70 16 is provided with a number of sockets spaced about the circumference of the disk. A pin 17, mounted in a stationary bracket 18, rests in one of these sockets to hold the shaft stationary.

To change the tension of the spring, the pin 17 is withdrawn and the disk 16 is rotated in the proper direction to produce the desired effect.

Attached to the lower edge of the curtain 80 is a reinforcing or stiffening bar 20, the extremities of which move in the guides 21 and 22, mounted on the sides of the opening in the wall. An angle-iron 23 is attached to the outside of the bar 20 and a 85 channel bar 25 is attached to the inside of the bar 20. These bars 23 and 25 serve not only to stiffen the lower edge of the curtain, but give it the desired thickness so that, when it is in the raised or in the lowered 90 position it will present a sufficiently large face to secure a fairly close joint. The channel member 25 is provided with a flange 26, which serves to seal the space between the fire door and the opening when the shutter 95 is in the raised position. This is shown clearly in Fig. 4.

The outer flange of the angle iron 23 is sheared off at the ends so that the upright portion can extend in the guides 21 and 22. 100

The channel bar 25 is made only of such length as to fit closely within the door opening. The tension of the spring 7 is so adjusted as to retain the channel member 25 in firm contact with the upper edge 28 of the opening and if it is desired to unroll the shutter it is necessary to overcome the tension of the spring 7. This is accomplished by means of a weight. The bar 30 which forms the weight for lowering the shutter is adapted to be dropped into the channel 27 of the bar 25 and is of sufficient weight to close the shutter. The bar 30 is normally raised from contact with the channel, and is suspended from the shaft 31 by means of hooks 32 attached to the bar, and lugs or arms 33 riveted to the shaft. It can be seen in Fig. 4 that rotation of the shaft 31 will release the bar 30 and cause it to drop into the channel 27. The weight of the bar is sufficient to close the shutter.

An arm 34 is attached to the outer end of the shaft 31 and is normally held in raised position, as shown in Fig. 3, to support the bar 30. A bell crank lever 36 mounted on a plate 37 attached to the outside of the casing 15 normally supports the weighted end 39 of the lever 34. The other end of the bell crank lever is attached to a wire 38 which contains fusible portions or links 40. The wire 38 is looped through an eye 41 attached to the end of the casing 15 to insure that the pull of the wire 38 will be at right angles to the arm and bell crank lever 36. The outer end of the wire 38 may be attached to any fixed point as 42. The ends of the bar 30 project beyond the end of the channel member 25 into guideways 43 and 44 on the sides of the opening or doorway. The guideways 21, 22 and 43, 44 are formed of a compound structure of angle bars. The bars 45 and 46 are placed with one side thereof against the wall and between the two parallel upstanding flanges, the flanges of angle bars 47 and 48 are secured. This compound structure is held together by rivets and is bolted or otherwise fastened to the edge of the doorway or opening. The compound bar is of considerable rigidity and stiffness and serves to guide the curtain or shutter and to prevent any leakage of air or gases past the shutter when the same is in the lower or closed position.

Flexible wire cables 50 and 51 are secured to brackets 52 and 53 mounted in the upper ends of the guideways 43 and 44, respectively. The wire cable 50, as shown in Fig. 4, extends the full length of the guideway and at the bottom thereof, the cable is passed to the outside of the compound bar and fastened by suitable tension means. The bar 30 is apertured at both ends to receive the cables 50 and 51 which form flexible guides for the bar 30. Handles 54 are

attached to the bar 20 at the bottom of the shutter to provide ready means for raising the shutter after the same has been lowered.

The operation of the device is as follows: When the fire door is set the parts are in the positions shown in Fig. 1. Upon the attainment of a sufficiently high temperature to fuse the links 40, the bell crank lever 36 will be released and will, in turn, release the weighted lever 34 attached to the shaft 31. The dropping of the end 39 of the lever 34 rotates the shaft 31 sufficiently to disengage the arms 32, 33, and thereby to release the bar 30. The bar 30 then drops into the channel 27 of the channel bar 25 and overcomes the tension of the spring 7 causing the shutter to unwind from the drum 6 and fall to the lower position, the channel 25 and the angle bar 23 sealing the opening at the bottom and the guideways 21, 22 sealing the opening around the edges of the shutter. The top of the doorway is closed by the casing 15, and thus the doorway is entirely sealed. To open the shutter the same may be raised by means of the handle 54 and it is necessary to lift only the difference in weight between the tension of the spring 7 and the weight of the bar 30. When the door has been raised to the upper position, it is necessary to relieve the channel 25 of the weight of the bar 30 or the shutter would immediately drop when released. This is accomplished by raising the arm 34 to the position shown in the figures. As the shaft 31 is rotated by raising the arm 34 the lugs 33 will engage the hooked arms 32 on the bar 30 and will support the weight thereof as long as the arm 34 is held in a raised position. The action of the cables 50 and 51 is important in this connection as it allows a twisting of the bar 30 while the same is being raised without the necessity of any lost motion in the guide. These cables, being flexible, do not cause any binding action and will allow the bar 30 to be angularly displaced as is necessary when the lug 33 is brought into engagement with the arm 32 to raise the bar 30. A similar action is obtained when the weight is dropped. The guiding cables insure that the weight will fall within the channel 27 and will not accidentally roll sidewise whereby it would be impossible for the lugs 33 to engage the arms 32 when it is desired to set the shutter. The tension on the cables 50 and 51 may be secured in any preferred manner.

It will at once be seen that a structure of great simplicity has been provided, and at the same time, absolute reliability of operation is secured. There is no opportunity for one end of the bar 30 to be dropped ahead of the other and even if the same should occur, the guiding cables 50 and 51 would prevent any binding or wedging of

the bar against the edge of the guideway. The function of the channel 25 is three-fold. In its upper position, it seals the casing 15 against the entrance of dust as well as holding the shutter at the proper distance from the bar 30. It also serves as a sealing member for the bottom of the shutter when the shutter is in its lower position.

It is obvious that any derangement of the apparatus will make itself apparent by the lowering of the shutter. Thus, if spring 7 should weaken or become broken, the shutter would drop of its own weight. Breaking of the wire 38 or of the levers 36 and 34 would cause the bar 30 to drop and close the shutter. Dropping of the bar 30 delivers a slight blow to the shutter and overcomes any tendency of the parts to stick, such as might be caused by rust, paint, or the like.

20 The present invention is an improvement of the structure invented by me and shown in Patent No. 1,077,468 granted November 4, 1913.

While my invention has been described with reference to the details of construction of a certain embodiment, it is not intended thereby, in any manner, to limit the invention, as it is clear that the same may be employed in other structures and in other relations and may be subject to numerous modifications apparent to those skilled in the art, all of which come within the spirit and scope of my invention.

What I claim as new and desire to secure by Letters Patent of the United States is:

1. In apparatus of the class described, a noncombustible shutter, normally held in a raised position, a weight to engage and to move said shutter to the lower position, a 40 rotatable shaft parallel with and bearing both ends of said weight, said shaft releasing said weight upon a partial rotation thereof, a guide to insure the correct engagement of the weight with said shutter, and means to hold said shaft against rotation.

2. In apparatus of the class described, a noncombustible shutter normally held in raised position, a channel member attached to said shutter, a suspended weight adapted to be released and to drop into said channel to move the shutter to its lower position, means for releasably suspending said weight, said means comprising a rotatable 50 shaft having a plurality of arms, hooks on said weight for engagement with said arms and a guide for the weight.

3. In apparatus of the class described, a noncombustible flexible shutter normally held in a raised position, a channel member attached to the bottom of said shutter, a weight adapted to be dropped into said channel to cause the door to move to lower position, means to raise said weight from

said channel, said means comprising curved arms on said weight, a rotatable shaft, arms on said shaft adapted to be brought into engagement with said curved arms by rotation of said shaft, and a guide member to hold said weight in position to cause said curved arms to be engaged by the arms on said shaft.

4. In apparatus of the class described, a weight having a plurality of hooks attached thereto, a guide for guiding said weight, a rotatable shaft having a plurality of arms for engagement with said hooks when said shaft is rotated, means to rotate said shaft to bring said hooks and said arms into engagement to support said weight, and means to hold said shaft against rotation.

5. In apparatus of the class described, a metal bar having hooks adjacent to each end thereof, a rotatable shaft having arms adapted to engage said hooks when said shaft is rotated, parallel flexible guides adjacent the ends of said bar, said bar engaging said guides and being guided thereby, means to rotate said shaft to bring said arms and said hooks into engagement, and means to hold said shaft against rotation.

6. In apparatus of the class described, a metal bar having a pair of curved arms attached thereto, a rotatable shaft having an arm adapted to engage said curved arms when said shaft is rotated, parallel flexible cables passing through apertures in the ends of said bar and forming a yielding guide for said bar, an arm attached to said shaft, means to hold said arm in raised position for retaining the arms on said shaft in engagement with said curved arms.

7. In apparatus of the class described, a metal bar having a curved arm near each end thereof, a rotatable shaft having arms adapted to engage said curved arms when said shaft is rotated, parallel flexible guides adjacent the ends of said bar, said bar engaging said guides and being guided thereby, a weighted arm attached to said shaft, means to hold said arm in raised position for retaining the arms of said shaft in engagement with said curved arms, said last means comprising a bell crank lever having one arm engaging said weighted arm and a fusible element normally holding the other arm of said lever.

8. In a device of the character described, a metal bar having a plurality of hooked arms attached thereto, a flexible shutter engaged by said bar to move said shutter to closed position, a rotatable shaft parallel with said bar and having lugs adapted to engage said hooks to support said bar, and means to hold said rotatable shaft against rotation.

9. In combination, a flexible shutter, a

spring roller supporting said shutter, a flange on the end of said shutter, a bar serving as a weight to move said shutter to the closed position against action of said 5 spring roller, a rotatable shaft parallel to said bar and having lugs for engaging said weight to support the same, and means to hold said shaft against rotation.

In witness whereof, I hereunto subscribe my name this 5th day of June, A. D. 1914. 10

MILLARD GILMORE.
